CLAIM

The ornamental design for a hockey jersey, as shown and described.

DESCRIPTION

FIG. 1 is an isometric front view of the hockey jersey closed; FIG. 2 is an isometric front view thereof, partially open; FIG. 3 is an isometric front view thereof, opened to greater extent than shown in FIG. 2;

FIG. 4 is a rear view of thereof; and,

FIG. 5 is a front view thereof.

The broken lines in the drawings are for illustrative purposes only and form no part of the claimed design.
